US00D927465S

(12) **United States Design Patent** (10) **Patent No.:** **US D927,465 S**
Wang (45) **Date of Patent:** **** Aug. 10, 2021**

(54) **COMBINED EARPHONES AND CHARGING CASE**

(71) Applicant: **SHENZHEN ZUNTE DIGITAL CO., LTD.**, Shenzhen (CN)

(72) Inventor: **Xiaohuai Wang**, Shenzhen (CN)

(73) Assignee: **SHENZHEN ZUNTE DIGITAL CO., LTD.**, Shenzhen (CN)

(**) Term: **15 Years**

(21) Appl. No.: **29/726,849**

(22) Filed: **Mar. 5, 2020**

(51) LOC (13) Cl. **14-01**

(52) U.S. Cl.

USPC **D14/223**

(58) **Field of Classification Search**

USPC ... D14/205, 207, 217, 221, 223, 224, 224.1, D14/225, 440; D24/173, 174

(57) **CLAIM**

The ornamental design for combined earphones and charging case, as shown and described.

DESCRIPTION

FIG. 1 is a perspective view of the charging case of the combined earphones and charging case showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the earphones of the combined earphones and charging case showing my new design;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the combined earphones and charging case, shown in an open configuration; and,

FIG. 18 is a perspective view of the combined earphones and charging case, shown in a closed configuration.

The broken lines in the drawings depict portions of the combined earphones and charging case that form no part of the claimed design.

1 Claim, 18 Drawing Sheets
